UNITED STATES PATENT OFFICE.

WILLIAM A. TROUT, OF LOS ANGELES, CALIFORNIA, ASSIGNOR TO EMSCO DERRICK & EQUIPMENT COMPANY, A CORPORATION OF CALIFORNIA.

FLEXIBLE CASING FOR OIL WELLS.

Application filed October 6, 1924. Serial No. 741,878.

My invention relates to the art of drilling wells and may be applied to both oil and water wells.

It has been the general practice for a considerable period to provide metal casing for both oil and water wells, seamless tubing threaded on each end provided with screw couplings being commonly used. Such casing can be readily inserted in the well and 10 is watertight under pressure when so installed. Casing of this type is generally known as screw casing.

It has been the practice for some time in water wells, and in some cases in oil wells, 15 to insert in the hole, particularly at the beginning of the well, what is known as stovepipe casing, this casing being made up of sheets of steel rolled into cylindrical form and secured together by rivets or otherwise, 20 as it is installed in the well, to form a continuous casing. Stovepipe casing has been principally used in the oil industry to hold out rocks, gravel and other loose formations which are encountered near the surface of 25 the ground before the more solid formations are encountered. When used in oil wells for this purpose, and as used in water wells, it is not necessary that the stovepipe casing be watertight, its purpose being merely to 30 prevent sand, gravel, or other loose material from falling into the well. Such stovepipe casing has certain very great advantages over screw casing, in that it is cheaper to manufacture, but it has the disadvantage 35 that it cannot be readily handled by the usual types of elevators used in oil well drilling, and the very great disadvantage that it cannot be used to shut off the surface water.

40 It is an object of my invention to provide a flexible casing built up from sheets of steel in a somewhat similar manner to the stovepipe casing which, when completed, will be watertight and which will be so constructed 45 that it can be readily handled in a manner similar to screw casing.

Further objects and advantages will be made evident hereinafter.

Referring to the drawings which are for 50 illustrative purposes only,

Fig. 1 is a perspective view partly in section showing the casing in the process of assembly.

55 Fig. 2 is a perspective view of a clamping ring.

Fig. 3 is a perspective view partly in section of the upper portion of a joint of such casing previous to its being secured to an adjacent joint.

Figs. 4, 5 and 6 are sections through various forms of joint which may be employed in this casing.

Fig. 7 is a view showing a portion of the completed casing and the method of handling same.

Fig. 8 is a section showing the method used for insuring complete galvanization.

My novel form of casing is made up of concentric cylinders of sheet metal, namely, inner cylinders 11 and outer cylinders 12, 70 these cylinders being formed of short lengths of sheet steel rolled into cylindrical form. The sheets 10 forming the inner cylinders 11 are each joined at their meeting edges 16 by welding. The sheet metal at each end 17 of each of the inner cylinders 11 is bent back on itself, as shown, preferably while the sheet is flat and prior to its being rolled into a cylinder. Each of the inner cylinders thus terminates in a rolled edge, the metal 75 turned back forming an annular ridge at each end of the cylinder.

The annular ridges 14 on adjacent inner cylinders 11 are then placed end to end and a split clamping ring 20 is secured therearound. This ring has inwardly projecting lips 21, and when sprung over and clamped in place around the ridges 14, it holds them rigidly in alignment and against axial displacement. The clamping ring 20 is then 80 welded along its edges 22, which are held together by clamping means, not shown.

This ring may be made, as shown at 90 in Fig. 5, without the lips 21 being formed of thicker material than the cylinders 11 and 12, thus forming a stiffening or strengthening ring but not being depended upon to lock the inner cylinders together.

The sheets of metal 30 forming the outer cylinders 12 are then rolled into cylindrical form and sprung over the joint formed by the ridges 14 and the clamping rings 20 or 90. Each of the sheets 30 is provided near its center with a rolled ridge 31 of sufficient axial length and diameter to clamp snugly about the clamping ring 20 when the edges 32 of the sheet 30 are pulled together by suitable clamps, not shown, the cylinder so formed fitting closely over the inner layer 11 of the casing. The edges 32 are then 110

welded and the clamps removed. It will thus be seen that the rings 20 and the outer sheets 30 serve to lock the inner cylinders 11 together. In some cases I omit the ring 20, depending wholly upon the ridges 31 which fit tightly over the ridges 14 for holding the inner cylinders together.

The sheets 30 forming the outer cylinders may be bent back on themselves, as shown in Fig. 6, to form ridges 35 at each end, or they may be left flat, as shown in Fig. 1. If left flat, the edges 36 of adjacent outer cylinders abut against each other and may be welded together. If bent back, as shown in Fig. 6, the ridges 35 may be locked together with a locking ring 38.

In practice I build up the casing in the shop in joints from 20 to 30 feet long, each joint of casing being made up of several inner cylinders 11 locked together by outer cylinders 12. It will be noted that the joints between the inner cylinders 11 come approximately in the center of the outer cylinders 12, being inside the ridge 31. The outer and inner cylinders, 11 and 12, being of the same length, the joints of the outer cylinders 12 come at about the center of the inner cylinders 11.

The assembled joint of casing as built in the shop consists of one less outer cylinder than the number of inner cylinders, so that at each end of the fabricated joint the last outer cylinder 12 terminates at a point 50, as shown in Fig. 3, and approximately one-half of an inner cylinder 51 projects therefrom.

The completed 20 or 30 foot joint of casing is then immersed in a galvanizing bath, for the purpose of protecting it against rust, locking its component parts together, and rendering it fluidtight. For the purpose of facilitating galvanizing, I provide, preferably in the outer cylinders 12, depressions 60 which are spaced a few inches apart and which hold the inner cylinders 11 and the outer cylinders 12 apart, leaving an opening 61 therebetween, as shown in Fig. 8. This opening 61 is of substantially uniform thickness and in the galvanizing bath is filled with spelter which adheres to both the inner cylinders 11 and the outer cylinders 12, forming a continuous bond and effectually closing cracks or joints in either series of cylinders.

The completely fabricated and galvanized joint is then ready for installation in the well. The ridges 31, as shown in Fig. 7, form collars against which an elevator 70 can abut and means by which the casing can be readily lifted.

The first joint being inserted in the well, it is supported on slips, not shown, with its upper end standing vertically, as shown in Fig. 3.

A second joint of casing can then be low-

ered until its lower end abuts on the upper end of the first joint, a previously galvanized ring 20 in its open position, as shown in Fig. 2, and a previously galvanized outer cylinder 12 in its open position, as shown in Fig. 1, being first slipped over either the first or second joint.

The ring 20 is then clamped over the adjacent ends of the first and second joints, and its meeting edges 22 are welded together. If it is desired to make a pressure-tight job, the edges of the lips 21 are also welded to the inner cylinders 11.

The outer cylinder 12 is then clamped in place, the ridge 31 fitting closely over the ring 20 and the cylinder 12 is welded along its edges 32. As previously explained, the ring 20 may in some cases be omitted, the outer cylinders 12 acting as locking means for the inner cylinders 11.

If it is desired to use the form of construction shown in Fig. 6, a locking ring 38 is then placed at each end of the outer cylinder 12, locking it to the outer cylinders already in place and galvanized into the first and second joint. The locking rings 38 may then be welded. Usually, however, the edges 36 of the outer cylinders 12 are not rolled and this edge on the outer locking cylinder is welded at each end to the outer cylinders of the first and second joints.

The first and second joints being joined as just described by a ring 20 and an outer cylinder 12, they form a continuous pipe which can be lowered into the well until the upper end of the second joint is in position to be similarly joined to a third joint. The process of adding joints and lowering is continued until the finished casing is landed on bottom at the desired depth.

The casing so produced has certain rather obvious advantages over ordinary screw casing. It may be fabricated from flat sheets near the point of utilization. Not only are the flat sheets cheaper to produce and easier to transport and handle, than the finished pipe, but they are not as liable to be injured by such transportation or handling.

It is also possible to use sheet steel having special characteristics, such as excessive hardness or toughness, which cannot be obtained in screw casing due to its process of manufacture.

The finished casing can also be made in considerably lighter weights per running foot than screw casing, due to the necessity of providing a certain rigidity in screw casing if its joints are to be made effective. The lighter casing made by my method is not only cheaper but it is much more flexible than screw casing and it readily accommodates itself to irregularities in the well bore, which would prevent the installation of or would seriously injure such screw casing.

My casing is also of substantially uniform

strength throughout its length, the method of securing the joints together in the field being much stronger than the common method of joining screw casing. It is also 5 of smaller outside diameter for a given bore, the joints shown in Figs. 4 and 6 consisting of only four thicknesses of thin sheet metal in place of the thick collars used on screw casing. By omitting the clamping ring 20, 10 and depending wholly upon the outer cylinder 12 as a locking means, as has been previously explained, my casing is only one thickness of sheet metal thicker at the joints than elsewhere. The joints being only 15 slightly larger than the body of the casing, it slips readily into even a tight hole in which the collars of screw casing might catch and hang. Since the friction on the outside of my casing is small, due to its 20 nearly uniform outside diameter, I am able to install it in holes into which screw casing could not be forced, and what is equally as important, I can pull this casing from such holes under conditions which would lock 25 screw casing beyond hope of recovery. As a result, a smaller hole can be drilled for a given internal diameter of casing, where my casing is used, than would be safe were screw casing used. This small diameter of hole results in considerable saving in drilling expense.

By making a casing which is reinforced at short intervals with annular ridges 31, I provide a casing that will hold its shape and 35 resist pressure much better than screw casing of the same weight per foot.

It is very common for screw casing, particularly in the larger diameters used in starting an oil well, to become split due to 40 strains to which it may be subjected, to its lack of flexibility, and to flaws in the casing, particularly along the welded seams. If, as is commonly the case, this split is not discovered until after the casing is permanently set 45 in the well, it ordinarily cannot be repaired but the well must be recased with a smaller diameter of casing at very great expense. Since my casing is thinner and made up of two layers, it is highly flexible, giving readily 50 under conditions that would split screw casing. Being rolled in flat sheets, the metal is homogeneous and will not split; or should a sheet be defective, the break or tear will not extend to the other thicknesses of metal 55 comprising the casing, which is made from an entirely different and entirely independent sheet.

I claim as my invention:

1. A stovepipe casing for wells comprising: 60 an inner layer formed of axially aligned sheet metal sections disposed in abutting relationship and having body portions, the abutting ends of said sections each being bent back along and in close contact with said body portions to form an external an-

nular shoulder; and an outer layer of sheet metal embracing the abutting end portions of adjacent inner sections including opposed annular locking ridges engaging said shoulders to lock said inner sections against axial 70 separation.

2. A stovepipe casing for wells comprising: an inner layer formed of axially aligned sheet metal sections disposed in abutting relationship and having body portions, the 75 abutting ends of said sections each being bent back along and in close contact with said body portions to form an external annular shoulder; a filler member encircling both abutting bent ends of adjacent inner sections; and an outer layer of sheet metal enclosing 80 said bent ends and said filler member including opposed annular locking ridges closely engaging said shoulders to lock said inner sections against axial separation. 85

3. A stovepipe casing for wells comprising: an inner layer formed of axially aligned sheet metal sections disposed in abutting relationship and having body portions, the 90 abutting ends of said sections each being bent back along and in close contact with said body portions to form an external annular shoulder; and an outer layer of sheet metal embracing the abutting end portions 95 of adjacent inner sections including opposed annular locking ridges closely engaging said shoulders to lock said inner sections against axial separation, said outer layer providing a horizontal annular abutment adapted for engagement by a well casing elevator. 100

4. A stovepipe casing for oil wells comprising: an inner layer formed of axially aligned sheet metal sections disposed in abutting relationship and having body portions, the abutting ends of said sections each being bent back along and in close contact with said body portions to form an annular external shoulder; a filler member surrounding 105 said abutting bent ends of adjacent inner sections; and an outer layer of sheet metal enclosing said bent ends and said filler member, said outer layer including an annular ridge which encloses said bent ends and said filler member. 110

5. A stovepipe casing for wells comprising: an inner layer of sheet metal made up of short inner sections; a turned rim on each end of each of said inner sections, said turned rims abutting against each other; a filler member situated outside said rims; and an outer layer of sheet metal fitting over and 115 contacting said inner layer including annular locking ridges fitting over said rims for securing the rims together. 120

6. A stovepipe casing for wells comprising: an inner layer of sheet metal made up of short inner sections; a turned rim on each end of each of said inner sections, said turned rims abutting against each other; a filler member situated outside said rims; and an 125

outer layer of sheet metal fitting over and contacting said inner layer including annular locking ridges fitting over said rims and enclosing said filler member for securing the 5 rims together.

7. A stovepipe casing for oil well use comprising: an inner cylindrical member, said inner cylindrical member being composed of cylindrical sections; turned cylindrical rims 10 on the ends of said sections, the rims of ad-

jacent sections abutting; and an outer cylindrical member, said outer cylindrical member entirely enclosing said sections including annular ridges which embrace said abutting rims.

In testimony whereof, I have hereunto set my hand at Los Angeles, California, this 30th day of September, 1924.

WILLIAM A. TROUT.
